US0D1039006S

(12) **United States Design Patent** (10) **Patent No.:** **US D1,039,006 S**
(45) **Date of Patent:** **** Aug. 13, 2024**

(54) **ICE PACK**

(71) Applicant: **YETI Coolers, LLC**, Austin, TX (US)

(72) Inventors: **Liza Morris**, Austin, TX (US); **Max Burtner**, Austin, TX (US)

(73) Assignee: **YETI Coolers, LLC**, Austin, TX (US)

(**) Term: **15 Years**

(21) Appl. No.: **29/897,825**

(22) Filed: **Jul. 19, 2023**

Related U.S. Application Data

(63) Continuation of application No. 29/786,921, filed on Jun. 3, 2021, now Pat. No. Des. 998,659.

CLAIM

The ornamental design for an ice pack, as shown and described.

DESCRIPTION

FIG. 1 is a front perspective view of an ice pack showing our new design;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a rear view thereof;

FIG. 8 is a front perspective view of a second embodiment

of an ice pack showing our new design;

FIG. 9 is a top view thereof;

FIG. 10 is a bottom view thereof;

FIG. 11 is a right side view thereof;

FIG. 12 is a left side view thereof;

FIG. 13 is a front view thereof; and,

FIG. 14 is a rear view thereof.
